UNITED STATES PATENT OFFICE.

CHARLES A. DRESSER, OF NEW YORK, N. Y., ASSIGNOR TO CLINE ELECTRIC MANUFACTURING COMPANY, OF CHICAGO, ILLINOIS, A CORPORATION OF ILLINOIS.

MOTOR-CONTROL SYSTEM.

Application filed June 7, 1923. Serial No. 643,831.

To all whom it may concern:

Be it known that I, CHARLES A. DRESSER, a citizen of the United States, and a resident of New York, in the county of New York and State of New York, have invented certain new and useful Improvements in Motor-Control Systems, of which the following is a specification.

The invention relates to systems for controlling the operation of electric motors that are used for driving large printing presses and like machines, and in which a master controlling member for the motor circuit is power-actuated under control of auxiliary switches to start and stop the printing press or other machine and increase or decrease its speed as desired. Auxiliary control switches are usually in the form of push buttons located at different stations on the press, each such station being usually provided with "stop," "inch," "increase" and "decrease" push-button switches for controlling the operation of the press as may be required from time to time, the "increase" and "decrease" push buttons being arranged to energize electro-responsive means which actuates the master controlling member to accelerate or decelerate the machine as long as one of these push buttons is held down. Such switches for increasing and decreasing the speed of the press can be satisfactorily employed at points at or near the machine and at which the operator may observe the operation of the machine and so avoid excessively increasing or decreasing the speed or stopping the machine. It is, however, sometimes desirable to control the speed of the press from a distant point and the present invention seeks to provide in connection with a control system such as outlined, a special controlling switch or push button for effecting the operation of the power-actuated master controlling member together with means automatically controlled by the master member for limiting or arresting the operation initiated by the special controlling switch.

The present improvement is particularly applicable to the control system of the motor or motors that operate large cylinder presses such as are used for printing newspapers, and with which the paper is fed in a continuous web from a roll. It is, of course, necessary at intervals to secure or paste the end of a fresh roll of paper to the web that

is being fed to the machine. It is necessary in effecting this operation to slow down the speed of the press but it is extremely desirable to avoid stopping its operation, if possible. Usually, however, the point at which fresh rolls are pasted or secured to the web is located at some distance from the press and often on a different floor. Hence, if the operator in charge of this work were provided with means similar to that used at the other stations for decreasing the speed of the press, he might easily, in attempting to decrease the speed, entirely stop it and thus afford considerable inconvenience. In accordance with the preferred arrangement of the present invention, a special "decrease" control or push-button switch is provided and is adapted to be located at the paper roll station and is actuated by the operator at that station when he wishes to decrease the speed of the press and attach a new roll to the paper web. This switch, in accordance with the preferred plan, is arranged to close the circuit of a relay which in turn closes the circuit of the pilot motor that actuates the master controlling switch member, the relay being arranged to close the circuit of the pilot motor for reverse operation and maintain the circuit closed so that the speed of the press is decreased until the circuit of the relay is opened. Means are also provided for opening the circuit of the relay when the master controlling switch is moved back to a predetermined point and the speed of the press has been reduced to a predetermined amount. With this arrangement the operator at the roll station can decelerate the press but he cannot reduce its speed below a predetermined amount or stop the press. Preferably also, an adjustable switch device is provided at the master controlling station for variably predetermining the speed to which the press will be decelerated when the special "decrease" switch at the paper roll station is operated.

The accompanying drawing diagrammatically illustrates the motor-control system with the preferred arrangement of the present improvement applied thereto.

In the arrangement shown, a master controlling switch *a* is located at the main station A and serves to control the circuits of a large motor *M* and a small motor *m*, the small motor being arranged to operate the press or other like machine at low speeds

and the large motor at higher speeds. The master controlling member α is actuated by a pilot motor P having oppositely wound series field coils 10 and 11, so that by closing a circuit through the pilot motor and through one or the other of the field coils, the master switch α can be moved forward or back to increase or decrease the speed of the press. The circuits of the pilot motor 5 are controlled by auxiliary "increase" and "decrease" push-button switches located at one or more auxiliary stations B, such stations being usually arranged at different points adjacent the press. Each of these 10 stations is also preferably provided as shown with "stop," "run-safe" and "inch" push-button switches. Another auxiliary station C adapted to be located at the roll station and at which point new rolls of paper 15 are attached to the web that is fed to the press, is provided with a "special decrease" push-button switch. The "stop" push buttons have normally engaged contacts; the "inch," "increase," "decrease," and "special 20 decrease" buttons have normally open contacts, and the "run-safe" are provided with contacts which are closed when the "run" button is depressed and open when the "safe" button is depressed. 25

The master controlling station is provided, as shown, with a line switch 12 which connects the mains 13 to the positive and negative supply conductors 14 and 15. This 30 station is also provided with electro-magnetic starting switches 16 and 17 for the small and large motor respectively. A no-voltage relay 18 and a relay 19 controlled by the "special decrease" push button are also located at the master controlling station. 35

In its initial or "off" position at the end of its movement in clockwise direction, the master controlling switch α engages a contact 20 and an insulated brush holder 21 40 on the master switch electrically connects a contact 22 to a contact bar 23. In this position a circuit is closed from the positive conductor 14 by a conductor 24, the switch arm α , contact 20, conductors 25 and 26, through the normally closed contacts of the "stop" push buttons in series, thence by a conductor 27, contacts 22, 21 and 23, and by a conductor 28 through the coil of the no-voltage relay 18 and thence by a conductor 50 29 to the negative main conductor 15. The no-voltage relay is thus energized to open a set of normally engaged contacts 30 and close two sets of normally open contacts 31 and 32. A circuit is then closed 55 from the positive main conductor 14 through the contacts 32 to conductor 26, thence through the contacts of the "stop" push buttons in series to conductor 27, thence by a conductor 33 through the contacts 31 60 and coil of the no-voltage relay 18 to the

return conductor 29. The operation of the relay 18 thus closes shunts around the contacts 20 and 22 of the master controlling switch and the relay remains energized during the movement of the master switch. 70 The relay contacts 31 and 32 also connect the conductors 26, 27 and 28 and the contact bar 23 of the master switch to the positive main conductor 14. These connections are, however, broken and the no-voltage 75 relay is deenergized when one of the auxiliary control "stop" push buttons is operated.

In the initial or "off" position of the master switch, the press can be operated at 80 slow speed by any one of the "inch" buttons provided the "run" buttons are depressed. In this case a circuit is closed from conductor 27 by a conductor 34 through contacts of the "run-safe" switches in series, thence by a conductor 35, the contacts of the depressed "inch" button to a conductor 36 and through the energizing coil of the starting switch 16 of the small motor to the return conductor 29. The operation of the 85 switch 16 will close a circuit from the positive conductor 14 by the conductor 24 through a resistance 37, and thence by a conductor 38 through the contacts of the switch 16 and the armature of the small motor to the negative conductor 15. The press will then start and operate at slow speed, with the entire resistance 37 in the armature circuit of the small motor m , until the depressed "inch" button is released. It is noted that the circuit is always closed 90 through the shunt field winding 39 of the small motor.

The master switch can be shifted in counter-clockwise direction from any position 10 by depressing one of the "increase" buttons to close a circuit from conductor 35, through the contacts of the depressed push button to a conductor 40, through the field winding 10 and armature of the pilot motor P , and thence through a resistance 41 and conductor 42 to the negative supply conductor 15. The pilot motor will then operate to move the master controlling switch α in counter-clockwise direction so long as the 11 "increase" button is held depressed, or until the master controlling switch α reaches the end of its path of movement in this direction and opens a pair of normally engaged contacts 43 interposed in the conductor 40. As the master switch α moves in counter-clockwise direction from its initial or "off" position, the insulated brush holder 21 thereon successively connects the contact bar 23 to two contact bars 44 and 45 which are connected by conductors 46 and 47 to the starting switches 16 and 17 respectively of the small and large motors, m and M . When the starting switch 17 is energized, a circuit is 12 closed from the positive main conductor 14 13

through its contacts, thence by a conductor 48 through the large motor M, and thence through the armature resistance 49 to the negative main 15. During the accelerating 5 movement of the master switch it successively engages a series of contacts 50 for cutting out different portions of the armature resistance 37 of the small motor, and then cooperates with a series of contacts 51 and a contact bar 52 to successively energize the circuits of a series of electro-magnetic switches 53 at the main station and which short circuit sections of the armature resistance 49 of the large motor M. The master switch 10 also cooperates with a contact bar 54 and a series of contacts 55 which are connected to the sections of a resistance 56 and by a conductor 57 to the shunt field winding 58 of the large motor. The counter-clockwise 15 movement of the master switch thus serves to accelerate the press.

It is noted that the "inch" and "increase" buttons will not serve to operate the press or increase its speed unless all of the "run" 20 buttons are depressed. However, whether or not the "run" buttons are depressed, the master controlling switch can be moved in clockwise direction to reduce the speed by actuating one of the "decrease" buttons. 25 When this occurs, a circuit is closed from the conductor 26 by a conductor 59 to the contacts of the depressed button, thence by a conductor 60 through the field winding 11 and the pilot motor. The latter is thus 30 operated in reverse direction to move the switch arm *a* clockwise and reduce the speed of the press as long as the operated "decrease" button is held down, or until the master switch *a* reaches its initial or 35 "off" position and opens a pair of normally engaged contacts 61 interposed in the conductor 60. At any time the operation of the machine may be arrested by pressing one of the "stop" buttons to open the circuit of 40 the no-voltage relay 18 and of the starting switches 16 or 17, thus cutting off the supply of current to either the large or the small motor, whichever is in operation. When this occurs the contacts 30 of the relay 18 are engaged and close a circuit from the positive main 14, through the conductors 62 and 60 and through the field winding 11 and pilot motor P, so as to move the master switch *a* in clockwise direction back 45 to its "off" position. Relay 18 cannot again be energized to prepare the controlling circuit for operation until after the master switch has returned to its initial or "off" 50 position.

If the "special decrease" push button is depressed when the motor is running above a predetermined speed, a circuit is closed from conductor 59 through the contacts of this switch, thence by a conductor 63 through 55 the coil of the relay 19, then through a re-

sistance 64 to the return main conductor 15, so that the relay is energized to close two sets of normally open contacts 65 and 66. The contacts 66 are interposed in a conductor 67 around the contacts of the "special decrease" push button, so that a holding circuit is completed, when the relay 19 is thus operated, and which maintains the relay in operating condition after the "special decrease" push button is released. The contacts 65 complete a circuit from the conductor 63 through a conductor 68 to the conductor 60, and thence through the field winding 11 and pilot motor P, and the latter operates to move the master switch *a* in clockwise direction and decrease the speed of the press.

The amount of decrease, however, is limited by closing a shunt circuit around the coil of the relay 19 when the master switch *a* reaches a predetermined point. This shunt circuit is controlled by a series of contacts 69 which are arranged to be successively engaged by the master switch *a* and which are connected respectively to a series of contacts 70, one or more of which may be engaged by an adjustable switch device or quadrant 71, this quadrant being also connected by a conductor 72 to the return conductor from the coil or relay 19. Thus, if it is assumed that the master switch *a* is in the position shown in the drawing and the adjustable switch device 71 is set as illustrated, the operation of the "special decrease" button will energize relay 19 and the decreasing operating circuit 100 of the pilot motor P, as described, to move the master switch *a* in clockwise direction and decrease the speed of the press until the master switch reaches the central contact 69 and closes a short circuit from the main conductor 14, by conductor 24, switch arm *a*, center contact 69, corresponding contact 70, switch device 71, conductor 72, to the return conductor from the coil of relay 19. The latter is then deenergized to open its circuit and the circuit of the pilot motor and arrest the decelerating movement of the master switch. In this way the decrease in the operating speed which can be effected by the "special decrease" button at the paper roll station is automatically limited and the stopping of the press is avoided. The speed to which the operation of the press can thus be reduced may be variably predetermined by adjusting the switch device 71 at the master station, it being desirable to prevent deceleration to a speed lower than is necessary.

It is noted that the contacts 69 extend in a series adjacent the "off" position of the master switch and correspond to a number of adjacent low speed operating positions of the master switch. It is also noted that the adjustable switch device 71, the movement of which is limited by stops 73, is arranged 115 120 125 130 135

to be electrically connected to one or a number of adjacent contacts 69 next to the "off" position of the master switch, and when the latter is in engagement with any such contact, the operation of the "special decrease" push button will have no effect.

Obviously an arrangement similar to that controlled by the "special decrease" and master switches could be employed for increasing the motor speed to a predetermined limit. Obviously too, the improvement could be applied to various motor-control systems and changes made in the details set forth without departure from the essentials of the invention as defined in the claims.

I claim as my invention:

1. In a motor-control system, the combination with a power-actuated controlling member for the motor circuit and a series of switches for controlling the operation of said member, of means controlled by said member, when one of said switches is operated, for automatically arresting said member at a predetermined point intermediate the ends of its path of travel.

2. In a motor-control system the combination with a power-actuated controlling member for the motor circuit and a series of switches for controlling the operation of said member, of means controlled by said member, when one of said switches is operated, for automatically arresting said member at a predetermined point intermediate the ends of its path of travel and an adjustable device for variably predetermining the point at which the controlling member is so arrested.

3. In a motor-control system, the combination with a master controlling member for the motor circuit and electro-responsive actuating means for said member, of manually operable "increase" and "decrease" switches controlling the operation of said actuating means, and means controlled by said master controlling member when in or moved to any one of a number of predetermined operating positions for preventing or limiting the operation effected by a special one of said controlling switches.

4. In a motor-control system, the combination with a motor, a master controlling member therefor and electro-responsive means for actuating said member in opposite directions to accelerate and decelerate the motor, of a series of push-button switches for controlling said actuating means, a holding relay controlled by one of said switches, and means controlled by said member for disabling said holding relay.

5. In a motor-control system, the combination with a motor, a master controlling member therefor and electro-responsive means for actuating said member in opposite directions to accelerate and decelerate the motor, of a series of push-button

switches for controlling said actuating means, a holding relay operated by one of said switches for maintaining the energizing circuit of said operating means, an adjustable switch device and means for de-energizing said relay controlled by the movement of said master member to a point determined by the setting of said adjustable switch device.

6. In a motor-control system, the combination with a motor, a master controlling member therefor and electro-responsive means for actuating said member in opposite directions to accelerate and decelerate the motor, of a series of push-button switches for controlling said actuating means, and means automatically controlled by the movement of said master switch member to a predetermined point intermediate the ends of its path of travel for limiting the operation effected by a special one of said push-button switches.

7. In a motor-control system, the combination with a motor, a master controlling member therefor and electro-responsive means for actuating said member in opposite directions to accelerate and decelerate the motor, of a series of push-button switches for controlling said actuating means, an adjustable switch device and a series of contacts controlled by said master switch member for automatically and variably limiting the operation effected by a special one of said push button switches.

8. In a motor-control system, the combination with a master controlling member and an actuating pilot motor therefor, of "increase" and "decrease" push-button switches for controlling the circuit of said pilot motor, a holding relay energized by a special one of said switches, and means controlled by the movement of said master controlling member to a predetermined point intermediate the ends of its path of movement for deenergizing said relay.

9. In a motor-control system, the combination with a master controlling member and an actuating pilot motor therefor, of "increase" and "decrease" push-button switches for controlling the circuit of said pilot motor, a holding relay energized by a special one of said switches, and means controlled by said master member for short circuiting said relay.

10. In a motor-control system, the combination with a master controlling member and an actuating pilot motor therefor, of "increase" or "decrease" push-button switches for controlling the circuit of said pilot motor, a holding relay energized by a special one of said switches, an adjustable switch device and a series of contacts co-operating therewith and with said master controlling member for short circuiting said relay at a point on the path of travel of

said member determined by the setting of said adjustable switch device.

11. In a motor-control system, the combination with a master controlling member, 5 a pilot motor for actuating said member and auxiliary switch means for controlling said pilot motor, of a special auxiliary switch for controlling said pilot motor to thereby move said master controlling member in decelerating direction, and means controlled by the movement of said member to one of its operating positions for limiting the operation effected by said special switch.

12. In a motor-control system, the combination with a master controlling member, a pilot motor for actuating said member and auxiliary switch means for controlling said pilot motor, of a relay for energizing and 20 maintaining the circuit of said pilot motor to move said master controlling member in one direction, a special auxiliary push-button switch for operating said relay and means controlled by the movement of said master member to one of its operating positions for disabling said relay.

13. In a motor-control system, the combination with a master controlling member, a pilot motor for actuating said member and auxiliary switch means for controlling said pilot motor, of a special "decrease" switch 30 for controlling said pilot motor and thereby move said master controlling member in decelerating direction, and means controlled by said master member in any of its positions between its "off" position and a predetermined operating position for disabling said special "decrease" switch.

14. In a motor-control system, the combination with a master controlling member, a pilot motor for actuating said member and auxiliary switch means for controlling said pilot motor, of a holding relay for closing and maintaining the circuit of said pilot motor to thereby move said master controlling member in decelerating direction, a special "decrease" switch for energizing said relay, and means controlled by said master member in a predetermined number 50 of its operating positions for deenergizing said relay.

15. In a motor-control system, the combination with a master controlling member, a pilot motor for actuating said member and auxiliary switch means for controlling said pilot motor, of a holding relay for closing and maintaining the circuit of said pilot motor to thereby move said master controlling member toward its "off" position, a special "decrease" push-button switch for energizing said holding relay, and means controlled by the decelerating movement of said member to a predetermined operating position for deenergizing said relay.

16. In a motor-control system, the com-

bination with a master controlling member, a pilot motor for actuating said member and auxiliary switch means for controlling said pilot motor, of a holding relay for closing and maintaining the circuit of said pilot motor to thereby move said master controlling member toward its "off" position, a special "decrease" switch for energizing said relay, means controlled by the decelerating movement of said member to a predetermined operating position for de-energizing said relay, and an adjustable switch device for selecting such operating position.

17. In a motor-control system, the combination with a master controlling member 80 for the motor circuit and electro-responsive actuating means for said member, of a manually operable switch controlling said actuating means to thereby effect the decelerating movement of said member, and means controlled by said master member when in or moved to certain of its operating positions adjacent its "off" position for preventing or limiting the operation effected by said controlling switch.

18. In a motor-control system, the combination with a master controlling member for the motor circuit and electro-responsive actuating means for said member, of a manually operable switch controlling said actuating means to thereby effect the decelerating movement of said member, means controlled by said master member when in or moved to certain of its operating positions adjacent its "off" position for preventing 100 or limiting the operation effected by said controlling switch, and an adjustable switch device for predetermining said operating position.

19. In a motor-control system, the combination with a master controlling member and a pilot motor for actuating said member, of a manually operable switch for controlling said pilot motor to thereby move said master controlling member in decelerating direction, and means controlled by said master member when in or moved to certain of its operating positions, adjacent its "off" position for disabling said controlling switch.

20. In a motor-control system, the combination with a master controlling member and a pilot motor for actuating said member, of a manually operable switch for controlling said pilot motor to thereby move said master controlling member in decelerating direction, means controlled by said master member when in or moved to certain of its operating positions adjacent its "off" position for disabling said controlling switch, 120 and an adjustable switch device for predetermining said operating position.

21. In a motor-control system, the combination with a master controlling member and a pilot motor for actuating same, of a 130

- 6 relay for energizing and maintaining the circuit of said pilot motor to thereby move said master member in decelerating direction, a push-button switch for operating said relay, and means controlled by said master member when in or moved to certain of its operating position adjacent its "off" position for disabling said relay.
- 5 22. In a motor-control system, the combination with a master controlling member and a pilot motor for actuating same, of a relay for energizing and maintaining the circuit of said pilot motor to thereby move said master member in decelerating direction, a push-button switch for operating said relay, means controlled by said master member when in or moved to certain of its operating positions adjacent its "off" position for disabling said relay, and an adjustable switch device for predetermining said operating positions.
- 10 CHARLES A. DRESSER.
